EARRING FASTENER

Michael Chernow, New York, N.Y., assignor to
Monocraft, Inc.

Filed July 19, 1971, Ser. No. 164,178

Term of patent 14 years

Int. Cl. D11—01

U.S. Cl. D45—09

FIG. 1

FIG. 2

FIG. 3

FIG. 1 is a perspective view of an earring fastener illustrating my new design;

FIG. 2 is a front elevational view thereof; and

FIG. 3 is a side elevational view, looking from the right with respect to FIG. 2.

I claim:

The ornamental design for an earring fastener, substantially as shown.
